ELECTRODE FOR THERMIONIC DISCHARGE DEVICES

Chester W. Castle, Maplewood, N. J., assignor, by
mesne assignments, to Radio Corporation of
America, New York, N. Y., a corporation of
Delaware

Application January 25, 1935, Serial No. 3,497

3 Claims. (Cl. 29—163.5)

My invention relates to improvements in electrodes for electron discharge devices, and more particularly to grid electrodes.

Multi-electrode thermionic discharge devices are well known in which there is mounted within an envelope a cathode surrounded by concentrically positioned grids, and an anode. In a well known screen grid type of tube for example, there is a tubular inner screen inside the tubular anode, and an outer tubular screen surrounding the anode and suspended at its upper end from a plate or so-called top shield. This cylindrical outer screen is secured to the top plate by clinching its upper edge under a flange at the outer edge of the top plate. The usual practice is to make this cylindrical outer screen of a sheet of woven wire mesh or punched sheet metal which is rolled into cylindrical form and the ends joined, either by welding or by folding the ends back upon each other to form a lock seam with interlocking flanges. Welding is rather expensive in view of the relatively slow processing thru which the screen grid must be put. With a lock seam difficulty has been experienced in positioning and clinching under the flange of the top plate the relatively thick seam, which includes four thicknesses of the screen grid stock. The lock seam, further, provides between the connected portions of the screen stock only a pressure contact which is found to be undesirable especially in high frequency operation.

An object of my invention is to provide a tubular electrode element for a thermionic discharge device which is simpler in construction and easier and less expensive to manufacture than the electrodes heretofore used.

A still further object of my invention is to provide a seamed tubular electrode having a wall thickness substantially the same at the seam as elsewhere and which readily lends itself to incorporation in thermionic tubes of standard construction wherein its assembly with the other elements of the tube provides a mechanically and electrically improved tube.

In accordance with my invention the tubular grid electrode is formed by overlapping the ends of the sheet of screen stock and securing the overlapped ends together by pressing them together with sufficient force to press the material of one end of the cylindrical stock into recesses in the material of the other end.

For a better understanding of my invention, however, reference may be had to the accompanying drawing in which Figure 1 shows the conventional lock seam screen grid; Figure 2 is a

perspective view and Figure 3 an end view of a screen grid embodying my invention; and Figure 5 shows a modified pattern of my seam; and Figure 4 shows in section and Figure 4a in plan a portion of my seam construction.

In many tube constructions in which a plurality of cylindrical grids are used, it is customary to support one of the grids, for example the outer screen, from a top plate or metal disc which is shaped much like the cover of a tin can and is secured to the upper end of the electrode assembly. The cylindrical tubular screen, of a diameter equal to that of the top plate, is conveniently secured to the lower side of the top plate by simply fitting the upper edge of the cylindrical screen into the top plate. This construction is shown diagrammatically in the upper part of Figure 2 of my drawing.

This construction is simple and cheap, but the usual four thicknesses of stock at the lock seam made as shown in Figure 1 causes difficulties in assembling the screen and top shield.

As shown in Figures 2 and 3, my improved screen electrode comprises a cylinder 7 formed preferably of wire mesh material. The ends of the stock 3 and 5 of this material are overlapped and joined, as shown at 9, by a seam which at the end which fits into the top plate is of no greater thickness than the mesh. In the construction of my type of screen electrode, this mesh cylinder 7 is slipped over a rounded mandrel and a multi-pointed hammer is caused to strike the stock along the longitudinal center line of the seam at spots or areas 11, whereby the material of the cylinder, which is preferably woven of nickel or other ductile metal, is compressed to such an extent that the individual wires or strands thereof are forced to flow into the recesses and spaces of the other overlapped end of the stock. So complete is the upsetting of the metal at the hammered portions of the seam, the finished product appears to be substantially of solid metal and free from openings. By the swaging action of the hammer the compressed portions of the wire stock appear to resemble solid sheet metal, the edges of which merge into the individual wires or strands of the wire screening.

The surface of the pressed portions of the seam may, according to my invention, be formed into any desired pattern. In Figure 5, for example a modification is shown in which the swaged spots along the seam are formed into parallelograms. By this construction a larger number of the circumferentially extending wires in the

screening stock are forced into the swaged areas of the seam. It is obvious from this construction that the seam is further strengthened.

Referring to Figures 4 and 4a, the swaged portion of the seam is shown in detail which clearly illustrates the manner in which the individual strands of the wire screening 3 and 5 are overlapped and flattened out to form continuous impervious mass 11 of sheet metal.

One method of joining the shield to its supporting plate may be understood by referring again to Figure 2, the upper part of which represents the top shield or supporting plate 13 for the screening element 1. In accordance with the usual practice, the edge of this plate is formed into a V-shaped flange, as shown at 15. Within the confines of the flange is inserted the upper edge of the cylindrical screening 7 which is secured in place by rolling the outer edge of the flange inwardly so as to clinch the upper rim of the screen cylinder. It is obvious that when using the four thickness seam, difficulty would be experienced in inserting the end of the seam within the flange 15 so as to produce a strong and neat appearing connection. This difficulty, however, is overcome by the screen made in accordance with my invention, since the seamed portion of the cylinder is of the same thickness as, or less than the thickness of, one layer of the stock. This provides a smooth connection between the grid cylinder and its top plate which is neat in appearance and strong in construction.

while the seam is uniform in manufacture and provides good electrical contact between the end portions of the screen stock.

It will be obvious to those skilled in the art that many modifications may be made in my device without departing from the spirit of the invention. It is accordingly desired that my invention be limited only by the prior art and by the appended claims.

What I claim as new is:—

1. In the art of seaming a wire mesh screen, the method comprising overlapping two portions of the screen to be seamed, and swaging spaced portions of the screen along the overlapped seam. 10

2. In the manufacture of thermionic tube electrodes formed of a wire mesh screen, the method comprising, rolling the screen to form a closed annulus, overlapping the ends of the annulus, and applying force to opposite sides and at spaced portions of the overlap to swage the wires 15 at said portions into flat substantially impervious sheets of metal of parallelogram surfaces. 20

3. In the manufacture of a thermionic tube electrode of the screen sheet type, rolled into the form of a cylinder, the method comprising overlapping the ends of the sheet material, and applying sufficient force to the overlapped material at spaced areas along the overlapped portion to interleave the component parts at said areas of the overlapped portions. 25 30
